2 Sheets-Sheet 2

The image contains three technical drawings of a stackable tray assembly:

- Fig. 4:** A perspective view of a stack of trays. The trays are rectangular with a grid of rectangular cutouts. They are held together by a central vertical stack of rectangular components labeled 11, which have semi-circular notches at the top and bottom. Labels 12 point to the vertical edges of the trays, 13 points to the side of a tray, 14 points to a top tray, 15 points to a top tray's corner, 16 points to a top tray's edge, and 17 points to a top tray's corner.
- Fig. 5:** A cross-sectional view of a single tray. It shows a central vertical stack 11 with semi-circular notches. A horizontal slot 12 is visible. Labels 12 and 20 are present.
- Fig. 6:** A cross-sectional view of the central vertical stack 11. It shows a central vertical component 20 with a horizontal slot 15. Labels 15, 20, and 21 are present.

WALTER M. CROSS, OF KANSAS CITY, MISSOURI

HEATER

Application filed February 16, 1925. Serial No. 9,439.

This invention relates to improvements in heaters, and refers more particularly to a furnace construction in which is positioned a plurality of connected tubes so arranged that the fluid medium circulated through the tubes will be more efficiently heated than in the usual type of furnaces where banks of tubes are positioned centrally in the combustion chamber or a separate heating chamber provided therefor.

Among the salient objects of the invention are, to provide a construction in which a plurality of heating tubes connected to form a continuous coil or manifolded as may be desired and arranged in either a single row or tier continuously around the four sides of the interior reflecting surfaces of the combustion chamber in juxtaposition or close proximately to the side interior walls or reflecting surfaces of the chamber; to provide a construction in which the tubes may be arranged in one or more rows or tiers in close relation to the interior side walls and upper reflecting surface or roof in a manner that the reflecting surfaces are reduced materially whereby the tubes containing the fluid medium are themselves reflecting surfaces receiving the radiant heat of the furnace directly, thus affording the more efficient heat exchange and eliminating the objection of excessively heating the reflecting surfaces; to provide a heater construction by means of which higher temperatures may be utilized in the combustion zone, as the heat is more readily transferred and removed from the combustion stage by the fluid medium contained in the tubes.

A further object is to reduce the side wall temperatures to a point where the brick work will not deteriorate due to excessive temperatures and to afford a more complete combustion by maintaining higher temperatures and increasing the percentage of carbon dioxide in the combustion gases without the formation of carbon monoxide, thus effecting a saving of fuel and producing optimum combustion conditions which consist of combustion gases having a minimum amount of air, a maximum amount of carbon dioxide and without material formation of carbon monoxide.

Referring to the drawings, the construction

shown has but a single bank of tubes in the combustion space, although it is understood that a plurality of tiers may be set in proximity to each of the side walls in place of the single tier.

55

Fig. 1 is a side sectional view of the heater.

Fig. 2 is a view taken along the line 2—2 in Fig. 1.

Fig. 3 is a view taken along the line 3—3 in Fig. 1.

60

Fig. 4 is a perspective diagrammatic view drawn to show the travel of the fluid medium through the connected tubes. The tubes are shown as a continuous pipe instead of showing the headers actually used in order to facilitate and simplify the fluid travel.

Fig. 5 is a view taken along the line 5—5 in Fig. 1.

70

Fig. 6 is a view taken along the line 6—6 in Fig. 1.

Referring to the drawings, at 1 is shown a heavily insulated heater whose walls are built of fire resisting material such as fire-brick, carborundum brick or similar refractory materials. Heat is supplied thereto by means of burners diagrammatically shown at 2. Centrally of the combustion chamber 3 is a checker-work brick wall 4 which serves to more uniformly distribute the heating gases. In the rear of the combustion chamber is a bridge wall 5 open at the top to permit the passage of the gases from the combustion chamber to the flue chamber 6 where they pass downwardly over the superheating tubes 7 and the preheating tubes 8 and out through the flue shown at 9 the tubes in the tube chamber acquiring substantially only convection heat as distinguished from the radiant heat acquired by the tubes disposed against the reflecting surfaces of the fire chamber and the roof of the tube chamber.

80

Briefly describing the travel of the fluid medium which may consist of liquid, vapors, or gases or mixtures of the same, they are introduced through the inlet line 10 and are circulated through the preheating tubes 8 in a manner shown in Fig. 4. From the preheating tubes the fluid passes through the transfer line 11 to the tubes 12 arranged along the interior side walls of the combustion

85

100

chamber around all four sides, the fluid rising to the next tube above at the completion of each circuit about the chamber. This circuitous travel is continued until the fluid reaches the tubes on a level with, or substantially on a level with, the rear bridge wall 5. At this point the travel is through the tubes designated as 13 which are positioned on the two interior side and front walls and are so connected by means of return bends to cause the fluid to shuttlecock back and forth about the three sides of the combustion chamber until it reaches the transfer line 14 by means of which the fluid is passed to the upper tubes 15 arranged against the upper reflecting or interior roof surface. On this upper surface the tubes are arranged and connected to zig-zag the fluid backward and forward in a continuous flow, the tubes being connected by return bends to course the fluid longitudinally of the heater, working from one side of the heater across to the opposite side where a transfer tube 16 passes the heated medium to the superheater tubes designated as 7. It will be noted that the tubes around the side walls are positioned only within the combustion chamber, while the roof tubes, or those laid against the upper reflecting surface, extend not only the length of the combustion chamber but also across the top of the flue chamber. From the superheater tubes the heated fluid medium is discharged through the line 18 to a vaporizer, collecting tank or any desired subsequent stage. Also, valves may be positioned in the inlet and outlet lines for the purpose of control.

In the corners of the combustion chamber are headers, such as those shown at 19. The tubes are connected into these headers and opposite the ends of the tubes are cleaning plugs 20 by means of which the tubes may be cleaned. Return bends 21 are used for connecting up the tubes positioned adjacent the upper reflecting surface. The construction of these return bends is diagrammatically shown in Fig. 6. These return bends are also fitted with cleaning plugs similar to those utilized in the corner headers.

Above the bridge wall at the rear of the combustion chamber, the corner headers will have only return bend connections as the tubes connect only into one face of the headers as distinguished from the lower portions of the same header and the header in the front corner of the combustion chamber where the tubes connect into two surfaces as shown in Fig. 5. It is understood that the corner headers are so divided that a continuous travel of the fluid medium is effected from the transfer inlet line 11 to the discharge line 14 through which the medium is discharged into the roof tubes 15.

The novelty in arranging tubes in this manner, adjacent and in close proximity to the interior side walls and roof, is to elimi-

nate materially the amount of direct radiant heat which is projected onto the side walls and interior roof surfaces producing deterioration due to the excessive temperatures present. In a heater where the tubes are positioned centrally in the combustion space, a considerable part of the heat absorbed by the tubes is reflected heat from the walls of the chamber and where high temperatures are an advantage objectionable deterioration is an ever present factor.

Where the tubes are positioned in close proximity to the side walls and where they cover at least 50% or more of the side wall and upper reflecting surfaces, they receive the direct radiant heat of the chamber and due to the fluid medium coursing therethrough carry away this heat more rapidly than tubes positioned centrally in a combustion space. A heater of this character affords a means for maintaining higher temperatures than have heretofore been usual, permitting more complete and efficient combustion or what might be termed as optimum combustion conditions wherein there is a minimum amount of air introduced, an increased percent of carbon dioxide and a substantial absence of carbon monoxide present in the combustion gases than has heretofore been possible under temperatures existent in a heater or furnace. For example, in an oil fired furnace the general practice is to have temperatures ranging from 1400° to 1800° F. and as high as 2000° F. where there is present carbon dioxide to the extent of approximately 7% under relatively satisfactory combustion conditions. In a heater such as that described in the present invention, temperatures as high as 2800° to 3000° F. may be maintained in the combustion chamber without deterioration of the brickwork and where combustion conditions are controlled to the extent that there is substantially no carbon monoxide formed and as much as 12% to 14% of carbon dioxide present in the combustion gases. Such conditions would realize great fuel saving while eliminating the objections of structural deterioration accompanying the present day practice.

It will be noted that the fluid medium coursing through the preheater travels in an opposed direction to the combustion gases, while in the super-heater tubes it is coursed in the same direction as the gases. This is to increase the efficiency and produce a better heat exchange.

This construction will furnish a heating surface per square foot within the combustion chamber which will absorb a larger amount of heat than is capable of being absorbed where the heating surface is put in the nested tube arrangement.

It is conceivable, also, that the tubes may be omitted from the rear reflecting surface or front face of the bridge wall in order to

obviate expansion difficulties and in case the tubes in the side walls are sunk partially in the masonry, the omission of these rear tubes would prevent disintegration of the brick-work occasioned by expansion and contraction.

Although for illustrative purposes the invention has been shown and described in connection with apparatus of more or less specific details of construction, arrangement and location of parts, and as embodying in its mode of operation a certain series and sequence of somewhat definite steps and operating conditions, it will be understood that many of the objects and advantages of the invention may be obtained to a greater or less extent through the employment of apparatus of modified character, or, in fact through variations or, in some case omissions, of certain of the component steps, without departing from the spirit and scope of the invention.

The present invention may be utilized in connection with the heating of liquids or vapors of any kind. It is particularly useful in the heating of hydrocarbon oils either in connection with their distillation in what in the industry is termed pipe still distillation, or in the connection with cracking installations or in the heating of water in steam boiler installation, the heater taking the place in the latter case of the boiler tubes and headers.

I claim as my invention:

1. A heater of the character described comprising a fire chamber and a tube chamber separated by an intermediate wall, a plurality of connected heating tubes disposed upon the interior side and upper reflecting surfaces of the fire chamber and roof of the tube chamber, separate banks of preheating and superheating coils in the tube chamber acquiring substantially only convection heat, serial connections between the separate units whereby a fluid medium may be circulated therethrough.

2. A heater of the character described, comprising a fire chamber and a tube chamber separated by an intermediate wall, a plurality of connected heating tubes disposed upon the interior side and upper reflecting surfaces of the fire chamber and roof of the tube chamber, separate preheating and superheating coils in the tube chamber, connections between the separate units whereby a fluid medium is circulated in an opposed direction to the heating gases in the preheater and in the direction of the gases in the superheating tubes.

3. In the process of cracking oil in a tubular oil heater, the improvement which consists in heating the oil in three stages, in the first of which the oil containing tubes are subjected to a countercurrent heating effect by heating gases previously cooled in the two succeeding oil heating stages, and in the second of which the oil is heated by radiant heat

absorbed from the combustion chamber of the furnace and the highly heated combustion gases, and in the third stage the oil containing tubes are subjected to a parallel current heating effect by heating gases partially cooled in the second oil heating stage.

4. A tubular oil cracking still comprising a combustion chamber, a heating chamber through which the heating gases are passed from the combustion chamber, two banks of tubes in said heating chamber extending transversely to the general direction of flow of the heating gases and successively traversed by the latter, tubular elements adapted to absorb radiant heat from the combustion chamber, and connections to and between said tubes and elements for passing the oil to be heated first through the tubes of the tube bank in the heat chamber last traversed by the heating gases, with a direction of oil flow therethrough generally counter to the direction of flow of the heating gases over the tubes, and then passing the oil through the radiant heat absorbing elements, and finally passing the oil through the tubes of the bank in the heating chamber first encountered by the heating gases, with a direction of oil flow through the last mentioned tubes generally parallel to the direction of flow of the heating gases over the tubes.

5. In an oil heater of the type comprising a combustion chamber, a heating chamber which is separated from the combustion chamber, a bridge wall over which the heating gases pass from the combustion chamber into the heating chamber which has a heating gas outlet at its lower end, and also comprising upper and lower groups of horizontally disposed tubes arranged in superimposed rows in said heating chamber, and conduit elements absorbing radiant heat from the combustion chamber and from the heating gases before the latter come into contact with said tubes, the improvement which consists in connections to said tubes and elements for first passing the oil successively through tubes of the lower group located at successively higher levels, and for then passing the oil through the radiant heat absorbing elements, and for finally passing the oil successively through tubes of the upper group located at successively lower levels.

6. In the process of heat treating a fluid medium in a tubular heater, the improvement which consists in heating the fluid medium in three stages, in the first of which fluid containing tubes are subjected to the countercurrent heating effect of heating gases previously cooled in the two succeeding fluid heating stages, and in the second of which the fluid medium is heated by radiant heat absorbed from the combustion chamber of the furnace and the highly heated combustion gases, and in the third stage the fluid containing tubes are subjected to a parallel current heating

effect by heating gases previously cooled in the second fluid heating stage.

7. In the process of heat treating a liquid in a tubular heater, the improvement which consists in heating the liquid in three stages, 5 in the first of which the liquid containing tubes are subjected to the countercurrent heating effect of heating gases previously cooled in the two succeeding liquid heating stages, and in the second of which the liquid 10 is heated by radiant heat absorbed from the combustion chamber of the furnace and the highly heated combustion gases, and in the third stage the liquid containing tubes are subjected to a parallel current heating effect 15 by heating gases previously cooled in the second liquid heating stage.

8. A heater of the character described, comprising a fire chamber and a tube chamber separated by an intermediate wall, a 20 plurality of connected heating tubes disposed upon the interior side and upper reflecting surfaces of the fire chamber and roof of the tube chamber, separate banks of preheating and superheating coils in the tube chamber 25 acquiring substantially, only convection heat, serial connections between the separate units whereby a fluid medium may be circulated therethrough, the tubes on the surfaces of said fire chamber being uncovered so 30 as to receive radiant heat.

9. A heater of the character described, comprising a fire chamber and a tube chamber separated by an intermediate wall, a 35 plurality of connected heating tubes disposed upon the interior side and upper reflecting surfaces of the fire chamber and roof of the tube chamber, separate preheating and superheating coils in the tube chamber, connections between the separate units whereby 40 a fluid medium is circulated in an opposed direction to the heating gases in the preheater and in the direction of the gases in the superheating tubes, the tubes in said fire chamber being uncovered so that the same may 45 receive radiant heat.

WALTER M. CROSS.
